ALFRED M. CHAFFEE, OF OXFORD, MASSACHUSETTS.

ART OF MAKING CLOTH-BOARDS.

1,083,593.

Specification of Letters Patent.

Patented Jan. 6, 1914.

Application filed May 17, 1913. Serial No. 768,207.

To all whom it may concern:

Be it known that I, ALFRED M. CHAFFEE, a citizen of the United States, residing at Oxford, in the county of Worcester and State of Massachusetts, have invented a new and useful Improvement in the Art of Making Cloth-Boards, of which the following is a specification, reference being made therein to the accompanying drawings.

10 This invention relates to a novel method of manufacturing cloth-boards of the character herein specified; the objects being to simplify the process and operations in the construction of articles of this class; to reduce the time and labor required in making and assembling the boards; to render their manufacture more economical; and to attain a more perfect, uniform and desirable product.

20 To this end my invention consists in a process of manufacture in which the materials are subjected to the treatments and manipulations substantially as hereinafter described and claimed; the order and nature 25 of said process being diagrammatically illustrated in the drawings, wherein—

Figure 1 is an elevation diagram representing the steps in my improved process. Fig. 2 is a plan view indicating the relation 30 in which the parts are assembled. Fig. 3 is an end diagram showing a primal stage of the assembling. Fig. 4 is an end view of the partially formed cloth-board as at the compressing stage, and Fig. 5 represents a preferred form of unattached frame members.

While I have illustrated the several steps of my improved process by showing certain means whereby the performance thereof may be facilitated, I do not confine my invention to any special construction of mechanism, as the means for practising it may be of different kind and arrangement.

The stock or materials employed for manufacturing cloth-boards in accordance 45 with my within described process, comprises longitudinal and transverse frame members, and a moderately thin paper fabric for the body covering of the same. The frame members as primarily prepared are 50 of the character shown in Fig. 5; all being of uniform thickness, the longitudinal members *a* being formed with semicircular outer edges and square inner edges; and the cross-pieces *b* are formed with square edges and 55 square ends adapted to abut against the inner faces of the longitudinal members.

In carrying out my invention in practice

the sheet or web of paper *P* for the body covering of the cloth-board, is taken from the supply or roll 1 and passed through a 60 moisture-laden or humidifying atmosphere, within a chamber 2 into which damp steam is admitted, or a source of vaporization maintained within the chamber to an extent that will impart to the paper any desired 65 degree of inherent moisture. The paper is then passed over a glue-supply roller 3, or glue-spreading device, and one side of the paper thereby charged with a surface coating of glue or adhesive substance. The 70 paper is then reversed about a guide-roll 4 to bring the glued face up, and by a suitable shear 5 a portion is cut therefrom of sufficient dimension for the entire body covering of a single cloth-board. This piece or 75 sheet *P** is placed upon a suitable table or form 6 furnished with end guides 7 and concave faced parallel guide-bars 9 and 10 that are positioned to indicate the dimensions of the particular size of cloth-board to 80 be made in any instance. The front and rear guide-bars, or one of them, are adjustable by any suitable means for contracting the form to a given extent for clamping purposes. Upon the glued surface of this sev- 85 ered sheet *P** I then assemble, individually, the unattached frame members, comprising the longitudinal side-bars *a* and the abuttingly disposed cross pieces *b* which are formed with square ends to match against 90 the flat inner faces of said side-bars; first placing the rear longitudinal side-bar or member upon the glue-coated top surface of the paper adjacent to the rear guide-bar 9, and crowding it down to place, which act 95 tends to elevate the rear edge of the paper; as per dotted line 11, Fig. 3. The cross-pieces *b* are next placed in position with their ends abutting against said first placed member, then the front longitudinal frame 100 member is placed against the ends of the cross pieces and in rear of the guide-bar 10, the frame parts being thus assembled in their proper relative positions, without nailing or any other preliminary attachment of the 105 frame members to each other, but disposed as indicated in Fig. 2. The guide-bars 9 and 10, beneath the paper sheet, indicate approximately the position at which the frame members are to be located and crowded down upon the top of the flatly spread glue-coated sheet. For convenience in practice one or both of the guide-bars are pref- 110 erably hinged or movable toward each other.

When the frame members are thus assembled the edges are forced inward, compressing the parts of the cloth-board together and turning up the front part of the paper sheet, 5 as indicated at 12, Fig. 4. While thus held under edgewise compression the rear edge 11 of the paper is folded forward and wiped or smoothed down upon the top of the frame, and then the front portion 12 of the 10 paper is folded rearward and smoothed down upon the first laid edge, its glued surface lapping upon and adhering thereto and to the frame. The freshly formed cloth-board C is then removed from the forming table and 15 placed upon a suitable supporting carrier 13 and subjected to a drying heat within a hot chamber 15 to dry out the moisture, so that the shrinkage of the paper and adhesion of the glue binds the parts firmly and 20 rigidly together; thus producing a superior cloth-board without requiring the use of nails in its structure, or the preliminary fastening together of the bars of the frame, thereby saving much time, labor and cost 25 in the manufacture.

What I claim and desire to secure by Letters Patent, is—

1. The improvement in the art of making cloth-boards of the character described, 30 which consists in preparatively moistening a sheet of paper fabric of suitable dimension for the entire body covering of the board, coating one side of said sheet with glue, assembled thereon loose unconnected frame 35 members comprising the parallel side-bars and intervening cross-pieces abuttingly disposed between the same, compressing the thus assembled parts firmly together in edgewise direction, closing inward, lapping 40 and wiping down the opposite remaining portions of the glued paper sheet upon the top of the frame members, then releasing the assembled board from compression and subjecting it to a uniformly complete dry- 45 ing action.

2. The improvement in the art of making cloth-boards, which consists in assembling a frame composed of a set of loose unattached longitudinal and transverse frame 50 members of the character described, upon a freshly glue-coated covering sheet adapted for inclosing said frame, the individual members of said frame being positioned in their predetermined order, compressing the 55 assembled parts edgewise, lapping the rear and front portions of the covering sheet, one upon the other, and smoothing the same flat down upon the assembled frame, and subsequently drying the whole.

3. In the art of making cloth-boards, the 60 process which consists in passing a web of suitable paper from its roll through a humidifying atmosphere or damp steamy va-

por, charging one surface thereof with a coating of semi-liquid adhesive substance, as 65 glue, drawing the end of the dampened glue-coated web to a position indicating the predetermined size of the board, and severing from said web a glue-coated sheet section of the proper dimension for the body covering, then assembling upon said sheet individually unattached frame members comprising parallel semi-cylindrical side-bars and intervening abuttingly disposed cross-pieces, forcing inward said parallel 70 bars for compressing the parts in edgewise relation, then smoothing down the upstanding rear and front edges of the paper upon the frame, then releasing the compression and transferring the fully formed cloth- 75 board in a supported condition through a dry heated atmosphere for eliminating the moisture from the board.

4. The improvement in the art of making flat skeleton-framed cloth-boards, which 80 consists in assembling the several members of which the frame is composed, in their independent unconnected condition, by placing the individual longitudinal and transverse members in contacting relation, properly disposed at the predetermined positions, upon an expanded shrinkable body-covering sheet, inclosing said individually assembled unattached members therein by winding 85 said sheet about the frame and uniting 90 said frame members rigidly and solely by the shrinkage and adhesion of said body-covering sheet embracing the exterior of the frame.

5. The improvement in the art of making 100 paper-covered flat cloth-boards, which consists in preparing a body-covering sheet of paper by passing the same through a damp-charged atmosphere, and applying to said sheet a coating of adhesive substance, then 105 forming directly upon the coated surface of said sheet a flat rectangular skeleton frame composed of independent front and rear side members and intermediately disposed unattached cross-pieces loosely laid in position, 110 the dimension of the sheet being such as to afford free portions that extend beyond the positions of said front and rear side members, turning upward the free portion of the sheet coincidently with the placing of said 115 side members; applying to the parallel sides inward edgewise compression, then continuing and completing the covering of said frame while the parts are so compressed.

Witness my hand this 15th day of May, 120 1913.

ALFRED M. CHAFFEE.
